UNITED STATES PATENT OFFICE.

FRED W. BAUM, OF NEWARK, NEW JERSEY, ASSIGNOR, BY MESNE ASSIGNMENTS, TO METROPOLITAN DEVICE CORPORATION, OF BROOKLYN, NEW YORK, A CORPORATION OF NEW YORK.

MULTIPLE-FUSE DEVICE.

Application filed February 8, 1923. Serial No. 617,665.

This invention relates to multiple fuse devices.

In commercial lighting and power installations the wiring, fuses and switches are covered by conduits and metal boxes for the purpose of fire protection and to prevent the theft of current before it has passed through the meter. The metal boxes contain the switches and fuses and in some types of boxes the meter is connected to the box. Such boxes when installed are sealed or locked to prevent tampering therewith and to prevent access thereto by unauthorized persons. Should a fuse blow out it cannot be replaced until an authorized person opens the box, unless the seal or lock is broken by an unauthorized person. To replace a fuse is moreover dangerous. Such boxes while serving as a protection and while completely enclosed, are obviously a great inconvenience in cases when a fuse blows out.

Attempts have been made to remedy such inconvenience by providing boxes in which the fuses can be removed and replaced by opening the part of the box containing the fuses without opening or exposing the part of the box containing the switch, it being necessary to open the switch before the fuse can be removed. Such a device is illustrated in the Kries Patent No. 1,224,880 patented May 1, 1917. In such devices the power can be easily stolen by anyone who knows how. Nor does the fact that the switch is open prevent dangerous shocks as in some types of boxes, the switch merely controls the load and not the power.

By my invention all of the advantages of the above described constructions are retained while providing means for conveniently changing fuses should one blow out.

The present invention utilizes fuses of standard shape such as the enclosed cartridge or plug types. Such fuses comprise a fusible element or wire of fusible metal which is enclosed in an insulating casing, the latter sometimes being packed with insulating material such as asbestos powder. The cartridge type fuse has at opposite ends metal caps or rings constituting the terminals of the cartridge and adapted to be inserted in clips,

The plug fuse which is called herein an enclosed fuse, is adapted to fit in a socket, the base or threaded shell of the fuse forming one terminal and the other terminal extending axially through the base. The fuse employed may be single enclosed fuses of the above types or preferably I employ multiple fuse devices of the enclosed cartridge or plug types, that is, an enclosed fuse having several wires or fusible elements enclosed therein capable of being successively used as they blow out, all capable of being easily removed and replaced, and all enclosed, at least when inserted in place.

The invention also utilizes as far as possible the standard fuse boxes in use, that is, the invention is characterized by simplicity of construction and arrangement of parts and by the ease and convenience of manipulation and of replacement of fuses, when necessary, and at the same time providing a safe, practical and efficient device which meets the requirements of underwriters and power companies and which will not cause the consumer annoying delays when a fuse blows out.

An object of the invention is to provide a practical, simple, safe and efficient fuse box which is inaccessible to unauthorized persons, yet allowing the changing of fuses should one blow out.

Another object of the invention is to provide a fuse box in which fuses may be easily inserted and removed when the box is open and providing means operable externally of the box to change fuses should one blow out, while maintaining the box closed and inaccessible to unauthorized persons.

Another object of the invention is to provide an externally operable fuse arrangement for a fuse and switch box which can be operated only when the switch is open.

Another object of the invention is to provide an attachment for cartridge fuse boxes to adapt the box for plug fuses embodying the invention.

Another object of the invention is to provide a single actuating means for controlling a plurality of multiple fuses in a manner to connect in circuit any fuse of one device with

any fuse of the other device, determined by the number of actuations.

Another object of the invention is to provide an improved enclosed fuse of the multiple type adapted for use in fuse boxes or for general use.

In the accompanying drawings I have illustrated several embodiments of the invention in which:

10 Fig. 1 is a plan view of one embodiment illustrating the use of fuses of the multiple plug type, the casing being broken away.

Fig. 2 is a sectional view on the line 2—2 of Fig. 1 looking in the direction of the arrows.

15 Figs. 3, 4 and 5 are detail views, on an enlarged scale, of a plug fuse which may be used in the embodiment of Figs. 1 and 2.

Fig. 6 is a plan view illustrating how a cartridge fuse type of installation may be 20 changed into a plug fuse type, enabling the use of the invention as embodied in Figs. 1 and 2, a portion of the casing being broken away.

Fig. 7 is a sectional view thereof on the 25 line 7—7 of Fig. 6 looking in the direction of the arrows.

Fig. 8 is a plan view illustrating another form of the invention, a part of the casing being broken away.

30 Fig. 9 is a sectional view thereof on the line 9—9 of Fig. 8, looking in the direction of the arrows.

Fig. 10 is a sectional detail of a locking means, on an enlarged scale and on the line 35 10—10 of Fig. 8 looking in the direction of the arrows.

Fig. 11 is a sectional view of another embodiment of the invention, parts being omitted.

40 Fig. 12 is an elevation of the device illustrated in Fig. 11.

Fig. 13 is an elevation, with parts in section and parts omitted, of another embodiment of the invention.

45 Fig. 14 is a sectional view thereof on the line 14—14 of Fig. 13, looking in the direction of the arrows.

Fig. 15 is an elevation, with the casing in section, of another form of the invention.

50 Fig. 16 is a detail elevation thereof, on an enlarged scale, with parts omitted and parts in section.

Fig. 17 is an end view and Fig. 18 is a side view on an enlarged scale of an enclosed 55 multiple fuse cartridge adapted for use in the forms of the invention illustrated in Figs. 15 and 16 and in Figs. 21 and 22.

Figs. 19 and 20 are similar views of an enclosed multiple fuse cartridge adapted for 60 general use.

Fig. 21 is a plan view, with parts omitted, illustrating how a plurality of multiple fuses may be actuated by a single lever or actuating means and Fig. 22 is an elevation thereof, with 65 the casing in section.

Fig. 23 is an elevation, partly in section, showing another modification.

Fig. 24 is a detailed sectional view thereof with the parts in separated position.

Fig. 25 is a detailed bottom plan of the 70 actuating mechanism shown at Fig. 23.

Fig. 26 is a plan view of the socket, parts being broken away.

Fig. 27 is an elevation showing another 75 modification, and

Fig. 28 is a plan thereof.

In Figs. 1 and 2 is illustrated a metal fuse and switch box 1 having a cover 2 hinged at one end 3 and adapted to be locked at the opposite end by means of a lock or seal 4. 80 Mounted within the box on the bottom is a base 5 of insulating material. Mounted upon the base 5 is a blade switch 6 having two blades, (one of which is shown) for controlling the lines and actuated from the exterior 85 of the box by means of a lever 7 journaled in the sides of the box, connected to the switch 6 and insulated therefrom. The power conduit and power wires (not illustrated) enter the box at any desired point through knock-outs (not illustrated) the wires being electrically connected to terminals 8. The conduit and wires to the local circuits (not illustrated) likewise enter the box, the wires being 90 electrically connected to the terminals 9.

95 Inserted in circuit between the terminals 8 and the blades of switch 6 are the threaded sockets 10 adapted to receive the fuses 11. The fuses 11 are of the enclosed multiple plug type which can be easily inserted into and 100 removed from the sockets 10 and which complete the circuits in the box through the terminals and switch.

In Figs. 3, 4 and 5 I have illustrated by 105 way of example the details of one of such fuses, known as a "six in one" fuse. This fuse comprises a porcelain member or piece 12 having secured to it and enclosing it a metal shell or thimble 13 formed with threads 14 whereby the fuse may be secured 110 in its socket 10. The upper end of the porcelain piece 12 is flanged at 15, the shell 13 being secured to a reduced portion of member 12. A member 16 carries the several fuse 115 wires or elements and is provided with a recess 17 into which the flange 15 fits. The body of member 16 is of insulating material. Upon the end of member 16 remote from recess 17 is a metal plate 18 (triangular as 120 shown for 6 fuses). To the corners of this plate are electrically secured the fuse wires 19 (six in number). The fuse wires 19 extend into holes 20 through member 16 and terminate in rigid terminals 21 in the holes 20. A metal conducting rod 22 secured at 125 one end to plate 18 extends axially through member 16 and through an axial hole 22a through the porcelain piece 12. A spring 23 is interposed between a head 24 on rod 22 and the porcelain piece 12 within the hole 130

22^a to draw the parts 12 and 16 together and to cause the head 24 to project beyond the lower end of the piece 12 and contact with a corresponding fuse receiving terminal in the 5 socket 10 when inserted therein. The ring 13 forms the other terminal of the fuse which cooperates with the socket terminal and may be electrically connected to any of the fuse terminals 21 in the following manner. A 10 metal pin 25 is slidably mounted in the porcelain piece 12 in a position such that upon rotation of member 16 relatively to member 12 the pin 25 can be positioned in any of the several holes 20 in contact with any terminal 15 21. The lower end of pin 25 is connected to the ring 13 by a flexible conductor 26. The porcelain piece 12 is cut away as indicated at 27 to allow free movement of the pin 25 and of the conductor 26. Interposed between 20 the piece 12 and a metal head 28 on pin 25 is a spring 29 to allow the relative rotation of the parts 12 and 16 over each other to a new fuse wire position and to insure that the head 28 will be forced into contact with a terminal 21 when the parts are 25 properly aligned. When it is desired to change from one fuse wire 19 to another the member 16 is raised against the tension of the spring 23 sufficiently to withdraw pin 25 from its hole 20 and is then rotated until the pin 25 enters another hole 20 and engages a new terminal 21. To further insure correct operation the member 16 is provided with six vertical grooves on slots 30 upon 35 vertical surfaces of the recess 17 while the flange 15 is provided with vertical ridges 31 adapted to mesh with the slots 30 and thus properly align the pin 25. When the member 16 is raised, the grooves and ridges disengage and when member 16 is rotated the ridges 31 ride over the portions 32 of member 16 until they align with a different set 40 of grooves 30 when the spring 23 forces them into place. When the member 16 is lifted the central terminal rod 22 is lifted out of engagement with the central socket contact and remains out of engagement until a new fuse wire is connected. All of the electrical 45 connections and wires should be properly protected and insulated. And obviously the multiple plug fuse may contain any desired or convenient number of fuse wires. The plug fuse above described forms per se no part of the invention and is shown and described in detail in United States Patent 55 1,227,256. Other types of plug fuse may be used such for instance as shown and described in United States Patent 1,335,810 in which the fuse is rotatable without axial 60 movement and can be replaced in part when exhausted.

Aligned with the sockets 10 in cover 2 are holes 35 through which the fuses 11 project when in place in their sockets.

65 The sockets 10 and fuses 11 are of a length

such that the fuses may be conveniently changed from outside of the casing by means of the rotatable and axially movable members 16. The fuses 11 not only fit the holes 35 closely to prevent access to the interior 70 of the casing 1 while they are in place but they are also provided with flanges 36 or means which prevent them from being pulled out while the cover is closed. All exposed parts of the fuses 11 are preferably covered 75 with metal caps 37 of which the flanges 36 preferably form parts.

The fuses 11 are screwed into their sockets 10 and then the cover 2 is closed around them and locked or otherwise secured against entry 80 by unauthorized persons. The flanges 36 prevent the several multiple fuses from being unscrewed from their sockets and pulled out. Should a fuse wire 19 of either fuse blow out a new fuse wire 19 can be placed in position 85 by lifting either member 16 and rotating it as above described. This can be done without opening the box and without waiting for someone to come to put in a new fuse. When the fuse wires of any multiple set are about 90 exhausted the cover can be raised and a new fuse plug can be substituted for the old one. Such fuse plugs of the enclosed multiple type can be available in quantities and can be placed in their sockets as is the present practice but only when the cover is up. Before 95 rotating any member 16 to place a new fuse wire in position the switch 6 may be opened.

While the invention is shown applied to a two wire system it is equally applicable to 100 a three wire system. The invention is applicable to bottom fuse switches in which the switch 6 is interposed between the source of power and the fuses but is especially of advantage in top fuse switches in which the 105 fuses are interposed between the switch and the source of power, (as illustrated in Figs. 1 and 2) in the latter case the switch controlling the load. In all cases, by the use of the present invention, shocks are prevented in the 110 replacement of fuses irrespective of the position of the switch and whether it is open or not. This is not true of switch boxes now in use.

Then also it should be noticed that in the 115 embodiment illustrated in Figs. 1 to 5 the central pin 22 is disconnected from its socket terminal when shifting to a new fuse wire position.

A feature of the construction above described is that the cover 2 can be opened without removing any of the parts of the fuse devices 11 and when the cover is in place the fuse devices are complete so as to be readily operated externally by anyone in case a 120 fuse blows out. The fuse wires of each 125 multiple fuse are completely enclosed and protected and the fuse device is readily removable and replaceable when necessary but not until the cover is opened. The invention 130

is simple, safe, easily operated and affording complete protection to the power companies against theft of current. It can be applied to existing types of boxes without revolutionary changes in their construction or arrangement of parts.

In Figs. 6 and 7 I have illustrated how the invention can be applied to certain constructions now in use. The box 40 has a pivoted cover 41 which is locked or secured when in use. Within the box is mounted an insulating block 42 having pairs of spaced clips 43 for inserting enclosed fuse cartridges therein and a blade switch 44 for controlling the lines. 10 one set of clips 43 being shown. This type of box includes a meter (not illustrated) which is inserted in an opening (not shown) in wall 45 of the box and is connected up in a well known manner. The attachment comprises a strip or piece 46 of insulating material on which are mounted plug fuse sockets 47 having terminals 48. Secured to strip 46 in electrical relation to each socket 47 are bridging conductors 49 (one of which is shown) which 20 may be secured to the clips 43 of each line, bridging the same, and thus supporting the member 46 and sockets 47 in position. The sockets 47 are adapted to receive the multiple plug fuses 11 of the character above described, these fuses extending through openings 35 in the cover 41 as previously described. The invention disclosed in Figs. 6 and 7 is identical with that described in connection with Figs. 1 to 5 except in the former it is described as an attachment whereby 30 existing cartridge fuse installations may be changed to the plug fuse type whereby the invention illustrated in Figs. 1 and 2 may be utilized.

40 In Figs. 8 to 10 is illustrated a form of the invention in which enclosed cartridge fuses of the nonmultiple type are employed. Such a fuse cartridge fuse comprises a tubular casing 50 capped by metal terminals 51 with 45 the fusible wire or element inside the casing 50 and connected to the caps 51.

The switch and fuse box 52 has a cover 53 hinged at 54, the cover being locked to prevent access to the box by unauthorized persons. The box illustrated is of the type to which a meter may be connected at the end 55 through an opening therein (not illustrated). Upon the porcelain base 56 within the box are the switch terminals 57 and fuse connecting terminals 58 and a pivoted switch 59 comprising blades (one being shown) adapted to engage and bridge contacts 57 to close the circuit. To the blades are secured insulating pieces 60 provided with slots 61. 50 A switch throwing lever 62 is pivoted in the sides of the casing 52 and is provided with a cross piece 63 riding in the slots 61. By swinging the handle 64 of the lever, the switch may be opened or closed from the outside of the box. The fuse terminals 58 are

70 mounted upon the base 56 upon opposite sides outside of the switch blades, one set being shown. One terminal 58 of each set is electrically connected to a pair of spaced clips 65 adapted to receive an end of an enclosed cartridge fuse CF and the other terminal 58 is electrically connected to an angular metal bracket 66 for pivotally supporting a multiple fuse device 67 of the present invention.

75 The multiple fuse device 67 comprises a metal head 68 having a plurality of sockets 69 and pivoted at 70 to ears on the outer end of the bracket 66. Secured within the sockets 69, preferably by means of set screws 71, are the ends of several cartridge fuses CF, 80 the opposite ends of the fuses CF being positioned to successively enter between and disengage the clips 65 to complete the fuse circuit. An insulating handle 72 is secured to each head 68 and extends at the opposite side 85 of pivot 70 through a slot 73 in the cover whereby either handle 72 may be swung in their slots to place any of the fuses CF into clips 65, the ends 74 of the slots acting as stops and being so located that either outer 90 fuse of each head is in the clips, when the handle is at one end of the slot 73 or the other.

95 A coil snap spring 75 is secured at one end 76 to the handle 72 at one side of pivot 70 and the opposite end 77 is secured to the bracket 66 at the opposite side of the pivot 70. When the handle 72 is swung to either side of its center position in its slot 73 the spring 75 throws or snaps one outer fuse CF or the other into the clip 65, the stops 74 limiting the movement of the lever 72 and cooperating with the spring 75 to insure complete engagement of the outer fuses CF and clips 65. 100 When the handle is positioned as shown the central fuse is in clips 65 and spring 75 is inactive.

105 To prevent access to the box 52 and to close the slots 73 I provide metal shields 78 mounted below the slots for movement with the handles 72 and preferably slidably mounted in guides 79 secured to the bottom of the cover, the shields 78 having holes 80 through which the handles 72 pass. While the shields 78 do not interfere with the operation of the levers 72 yet they prevent access to the box while the cover is closed and provide a completely enclosed box while allowing operation of the fuses externally.

110 In some cases it is preferable that means be provided to lock the several multiple fuse devices 67 against movement or change until the switch 59 is first opened. In the embodiment illustrated in Figs. 8, 9 and 10 I have shown a locking means which may be used. 115 This locking means comprises for each multiple fuse device a pair of pins 81 slidably mounted in bearings in each insulating plate 60 of the switch 59 and adapted to engage opposite sides of any cartridge fuse CF which 120

is in the fuse clips 65. The inner ends of the pins are provided with conical heads 82. Interposed between the heads 82 and the bearings are coil springs 83 tending normally to withdraw the opposite ends of the pins away from the opposite sides of the clipped fuse. Stops 84 are provided upon the pins at the opposite sides of their bearing to prevent the springs 83 from forcing the pins out of their bearings.

Mounted upon the porcelain base 56 between the switch blades is a stationary cam 85 having inclined surfaces 86 adapted to coact with the conical heads 82 of the pins 81. The operation of the device or locking means is as follows: When the switch 59 is opened the pins 81 are raised with it, the inclined surface 86 allowing the heads 82 to move inwardly as the pins are raised and until finally the heads disengage the cam. The pins 81 then disengage the fuses, the springs 83 forcing them back out of the way. When a new fuse is properly clipped in by handle 72, the switch 59 is closed and the conical heads 82 engage the cam 85 and the pins 81 are forced inwardly to lock the multiple fuse devices against actuation or movement. The locking device may be omitted if not required or if desirable.

The form of the invention illustrated in Figs. 8 and 9, like the form illustrated in Figs. 1 and 2, allows the replacement of a blown out fuse without opening the box. The fuse illustrated is of an enclosed standard type. By actuating the handles 72 one way or the other any of the fuses of each multiple fuse installation within the box may be moved into clipped position and may be maintained in clipped position by means of the spring clips 65, assisted by spring 75 when the handle is against either stop 74. Each multiple fuse head 68 is adapted for three fuses. Any desired or convenient number of fuses may be employed however and the device is operative until all the fuses of either installation have blown out. It will then be necessary to open the box. This can be done by an authorized person, such as an employee of the power company. To open the box all that is necessary is to lift the cover. The handles being of such a character to allow this without first removing any parts. To replace any of the fuses within the box the handle 72 is, after the box is opened, tilted back so that it lies against the outer angular portion 87 of the fuse conducting bracket 66. The snap spring 75 tends to hold the handle in that position with the fuse head 68 and its fuses so located as to be away from the terminals 58 and clips 65 and as to be convenient for replacing cartridge fuses without danger of shocks.

In Figs. 11 and 12 is illustrated another form of the invention. This form like the one just described involves the use of enclosed cartridge fuses but of a special design

in which the cartridges are arranged in tandem or in alignment and can be moved axially to successive operative positions. This fuse 88 comprises sections 88^a and metal end terminals 89 and separate fixed intermediate metal terminals 90, the intermediate terminals 90 being common to adjacent fuse sections and the several fuse sections being preferably connected together. The fuse wires or elements (not shown) are connected in series between the successive terminals 89-90.

The device 88 is mounted in a closed fuse box 91, for example, of the character illustrated in Figs. 1 and 2 or 8 and 9, one such device being inserted in each line. The box 91 also contains a switch (not shown) for controlling either the load or the power. For each fuse device 88 there is provided in the box 91 spaced clip terminals 92 adapted to engage and electrically connect the several sections of the fuse device 88, engaging the terminals 89 and 90 thereof. The terminals 92 are mounted centrally within a tube 93 preferably of insulating material and in this tube 93 through removable plug 93^a is placed the multiple fuse 88. Between an end of the fuse 88 and the end 94 of the tube 93 is a coil spring 95 tending normally to force the tandem fuse 88 to the opposite end of the tube.

Engaging the opposite end of the tandem fuse is an insulating plunger 96 having a handle 97 projecting through and ridable in a slot 98 in the tube 93 and extending through a step like slot 99 in the side of the fuse box 91. Fig. 12, the handle terminates in a ring 100 outside of the box whereby it may be actuated. The slot 99 comprises vertical portions 101 connected by inclined portions 102. The vertical portions hold the handle 97 locked against movement due to spring 95 and are so located as to hold the successive sections 88^a in the clips 92. Should the left-hand fuse section (Fig. 11) blow out, by pulling the handle 97 to the left through the inclined slot 102 and allowing it to snap into the middle vertical portion 101, fuse 88 is moved back against the tension of spring 95 and the second tandem fuse section 88^a is placed in the clips 92, the handle having sufficient resiliency to allow it to ride up the incline and then to snap down into place locking the fuse 88 in position against movement due to the spring 95. The number of steps in the step like slot 99 will vary with the number of sections 88^a in the tandem fuse.

To lock the handle 97 in each position, to close the slot 99 against access to the box therethrough by unauthorized persons and to completely enclose the box when in use, there is provided a combined lock and shield 103 which also prevents the changing of the fuses until the switch within the box is first opened. For this purpose to the switch control handle 104 which is of the usual construction such as illustrated in Fig. 1, is se-

cured the plate or shield 103 which is arranged to extend down over the slot when the switch is closed and to be moved upwardly out of the way when the switch is open. The lower edge of shield 103, which is secured to the switch handle inside the casing, is provided with a plurality of notches 105 arranged to align with the vertical portions 101 of the slot 99 and to straddle the handle 97 at any 10 of its locking points in the side of the casing or box.

With the construction disclosed the handle 97 can not be actuated until the switch is first 15 opened, unlocking it and allowing its movement in the slot 99, the slot being completely closed at all times when the switch is closed. The combined locking means and shield may be omitted, if not required or if desired.

The multiple fuse arrangement illustrated 20 in Fig. 11 is of the enclosed type making it safe against fire and is of a type which may be easily replaced when all the fuses are used up. The fuse sections 83^a instead of being secured together may be placed in alignment 25 as cartridges are placed in a magazine and in such case the standard enclosed type of cartridge fuse may be employed.

In Figs. 13 and 14 is illustrated another 30 form of the invention utilizing an enclosed fuse of the single fuse type above described, which is standard and may be purchased in the open market. The multiple fuse devices 106 illustrated each comprises a rotatable support 107 mounted and secured to a shaft 108 35 journaled at its inner end in a bearing 109 within the box 110 and at its outer end 111 in a bearing in the side of the casing or box 110 handles 112 being provided on the outside of the casing 110 for rotating the shafts 108. Mounted upon the insulating or porcelain block 113 in the box are pairs 40 of fuse receiving terminals or spaced fuse clips 114. The rotatable supports 107 are provided with openings or holes 115 in each of which may be secured transversely thereof an enclosed fuse, CF having the usual metal terminals 51. These fuses are secured transversely of the rotatable mountings 107 within the holes 115 by any suitable means such as the set screws 116 engaging the centers of the fuses. The supports 107 are so mounted relative to the clips 114 that upon their rotation the cartridge fuses CF mounted thereon may be successively 45 moved into clipped positions with their metal heads secured in and in contact with each part of spring clips 114. The clips are arranged relatively to the rotatable supports 107 to allow a cartridge CF when rotated to 50 enter at one side of the clips and to move out of engagement therewith at the opposite side. It is to be understood that the arrangement of the two sets of multiple devices may be 55 changed. For instance they may be arranged with their axes parallel to each other 60

instead of in alignment. The multiple cartridge devices illustrated in Figs. 13 and 14 provide means whereby fuses may be changed from the outside of the box while maintaining the box inaccessible to unauthorized persons and completely closed. The fuses, being of the enclosed type and of a standard form, may be easily replaced when the fuses of either set are used up. 70

In Figs. 15 and 16 is illustrated a form of 75 the invention in which a multiple fuse cartridge MFC of the enclosed type is utilized, details of the fuse being shown in Figs. 17 to 20.

The fuse illustrated which is an improvement upon the construction of United States Patents Nos. 1,254,490 and 1,268,807 in which the details of construction are shown and described, comprises a tubular casing 117 of insulating material in which are enclosed a 85 plurality of fusible wires 118 (in the form illustrated, four in number) all electrically connected at one end to a fixed metal cap 119 and terminating at their opposite ends in spaced pin like terminals 120 fixed in openings 121 in the opposite end of the fuse body. A metal cap 122 is rotatably and axially movably mounted on this end of the fuse, constituting the opposite exposed terminal of the cartridge. Any of the fuse wires 118 may 95 be electrically connected to the cap 122 by means of a springy tubular terminal connector 123 secured to cap 122 and adapted to telescope around each pinlike terminal 120, forming a good contact and electrical 100 connection therewith (see Fig. 20). In order to connect the cap 122 to a different fuse wire all that is necessary is to lift the cap sufficiently to disengage the tubular connector from one of the terminals 120 and then rotate the cap until the connector 123 is aligned with the next terminal 120 and then press down the cap engaging the terminal and connector. 105

I have improved the construction of such 110 fuses by providing means for guiding the cap 122 from one fuse connection to the next whereby the change can be made quickly and efficiently by a person by hand or whereby such a fuse may be utilized as an externally 115 controlled device for the fuse boxes of the present invention. The means employed comprises rifling, cam grooves or slots 124 either on the rotatable cap 122 or on a ring 125 secured to the end of the tube 117 under 120 cap 122 as illustrated in Figs. 18 and 20 and cooperating with a pin or set screw 126 riding therein and secured to the cooperating relatively rotatable member, in the case illustrated the rotatable cap 122. The rifling 125 124 comprises a plurality of longitudinal or axially extending portions 127 spaced around the cartridge and equaling in number the fuse terminals 120. These longitudinal portions 127 are of sufficient length and so lo- 130

cated as to allow sufficient axial movement of the cap 122 to completely engage and disengage the terminals 120. The portions 127 are connected by angular grooves or camways 128 comprising a part sloping transversely towards the end of the fuse and a communicating part having a steeper slope in the opposite direction from the corner 129 to the next longitudinal portion 127, the two communicating parts between adjacent portions 127 forming the corner 129. The arrangement is such that when the cap 122 is raised or moved outwardly axially it will be determined to rotate in one direction, the pin 126 riding in the angular portion 128 to the corner 129 when the outward movement is stopped. The cap 122 is then pushed down. The corner 129 is so arranged that when the cap is pushed down the pin 126 must ride in the steeply inclined part into the next longitudinal portion 127, further rotating cap 122 sufficiently to make the connection to the next fuse wire.

With a fuse constructed as above described the changes can be made unconsciously as a vertical pull on the cap 122 to its outer limit and then a push on the cap serves to remove the connector 123 from one terminal and places it on the next, the necessary rotation being caused by the grooved connections between the longitudinal portions 127. When such a fuse is to be sold commercially or separately it is provided with a spring clip 130 secured to the cap 122 and adapted to engage the several depressions 131 on the ring 121 to hold the cap 122 in place when depressed, maintaining good electrical contact.

In Figs. 15 and 16 I illustrate how multiple enclosed cartridge fuses MFC of the type shown in Figs. 17 and 20 and above described may be utilized in a fuse box. Such box 132 is of the type previously described and comprises a cover 133 which is pivoted. An insulating base 134 having a switch 135 mounted thereon is located within the box 132. The base 134 also supports the fuses, two or more. The electrical connections into and out of the box and to and from the meter, being well known, are not illustrated.

Mounted upon the insulating base are fuse connecting terminals or sockets 136 (one being shown) in which the fuses MFC may be firmly secured at their ends 119 by any suitable means such as set screws 137. In the embodiment illustrated the fuse is at right angles to the cover. The opposite end of the fuse or rotatable cap 122 is supported by and between and electrically connected to the spring clips 138 on the upper end of a metal bracket 139 forming the opposite fixed terminal of the fuse and mounted on base 134. The arrangement of socket 136 and clip 138 is such that the fuse may be easily removed therefrom, the clips 138 permitting the movement of the cap 122 for changing fuse wires.

For use in fuse boxes the rotatable cap 122 is preferably provided with a lug 140 to which may be secured preferably by means of a set screw 141, an insulating rod 142. The rod 142 is of sufficient length to extend through the box, or as here illustrated, the cover 133. The end of the rod outside of the box is provided with a swiveled ring 143 whereby the rod may be actuated. Mounted on the rod or handle 142 within the box are spring abutments 144-145, the inner one 144 of which being fixed to the rod and the outer one 145 being slidable on the rod. Around the rod and interposed between the abutments is a coiled spring 146. The cover 133 is provided with a slot 147 of sufficient size to allow the ring 143 to pass through it when the cover is opened. The upper abutments 145 closes this slot however when the cover is closed. When the cover is closed with the rod 142 projecting through the slot 147, it engages the upper abutment 145 holding it stationary and thereby compressing the spring 146 which forces the rotatable cap 122 down.

When it is desired to change to a new fuse wire connection all that is necessary is to pull out on the ring 143 as far as it will go and then release it. The spring 146 then forces the cap 122 downwardly connecting a new fuse wire, the action being, in a way, automatic by reason of the construction illustrated in Figs. 17 to 20. In order to prevent lateral displacement of the rod 142 due to the rotation of the cap 122, the cover 133 is provided with depressions 148 fitting around the upper abutment 145 to hold it in place. When the fuse wires in any cartridge MFC are used up the cover 133 may be unlocked and opened, the ring 143 holding the upper abutment 145 in place on its rod. The rod 142, can now be disconnected from the fuse cartridge MFC and the exhausted cartridge removed and a new one inserted and connected to the handle. The cover is then closed and locked and the device is ready for operation again should a fuse blow out.

In Figs. 21 and 22 I illustrate means for actuating a plurality of multiple fuse devices such as multiple cartridge and plug fuses, by means of a single instrumentality or member whereby different combinations of the fuse wires of the several multiple fuses may be placed in the circuits. The invention is illustrated applied to the type of fuse shown in Figs. 17 to 20 and above described although it is applicable to all types of multiple fuse devices.

The box 132 illustrated is of the enclosed type like those previously described being provided with a pivoted cover 133 and having therein a porcelain base 134 with a switch (not illustrated) thereon but like that previously described.

The several enclosed multiple fuse cartridges MFC are mounted in the box in fuse

connecting terminals, fuse clips or sockets and are arranged flat upon the base. The fixed terminals 119 of the fuses are rigidly secured upon base 134 in sockets 136 by means of set screws 137 whereby a pull may be permitted on the fuse to actuate the rotatable fuse cap 122. A pair of spring clips 138 mounted upon the base embrace opposite sides of the rotatable cap 122 of each fuse forming an electrical connection therewith while allowing its fuse changing movement, the clips 138 preferably extending beyond the caps 122 as illustrated to maintain full contact as the cap is moved axially. The socket 136 and clips 138 form the fixed terminals of the fuse within the box, allowing its easy removal.

Arranged transversely within the box and journaled in the opposite sides of the box is a U shaped actuating member 149, positioned to be connected to the several rotatable caps 122 of the fuses. Connected centrally to the member 149 is a handle 150 which extends through a slot 151 in the cover and through a hole in a shield 152 slidably mounted in slideways 153 on the bottom of the cover for the purpose and in the manner described in connection with Figs. 8 and 9.

Secured preferably by set screws 154 to the lugs 155 of the movable fuse caps 122 are the stems 156—157 one 156 of which is permanently connected to the actuating member 149 and the other 157 of which is periodically or intermittently so connected. The actuating member 149 is provided with slotted lugs 158 extending transversely of stems 156—157. The stem 156 extending through the slot of one lug 158 is connected permanently to the actuating member by means of heads 159 engaging opposite sides of the lug and secured to stem 156. The other stem 157 likewise extends through the slot of the other lug and is provided with a head 160 between its lug 158 and its fuse cap, the actuating member 149 being free to move in one direction without pulling stem 157 with it, but when moved in the opposite direction to engage head 160 and force the stem 157 back and hence its cap.

Secured upon the permanently connected stem 156 is a wheel 161 having a spring cam 162. The spring cam 162 is secured at one end 163 to the periphery of the wheel, diverges outwardly therefrom for about a quarter of the circumference of the wheel and then forms an inwardly directed step 164, the free end 165 of the cam spring entering a slot or recess 156 in the periphery of the wheel. Slidably mounted in bearing lugs 167 upon the actuating member 149 is a transverse rod or pin 168 having a head 169 at one end engaging the cam wheel 161, a spring 170 being interposed between the head and one of the bearing lugs 167 for maintaining their engagement and for normally holding the

rod 168 in a left hand position. The opposite end of the rod is provided with a semi-cylindrical recess 171 adapted to engage the opposite stem 157. Stem 157 has a reduced portion 172 forming a circumferential groove 70 in which the end of the rod 168 periodically fits to connect the stem 157 thereto to enable its actuation by means of the handle 150. The rod 168 is mounted in its bearings non-rotatably, preferably by making the rod angular in cross section and likewise its bearings. A pair of springs 173 are so connected to the actuating member 149 and to the box 132 as to normally hold the member in a position tending to hold the rotatable caps 122 86 firmly upon the ends of their fuses.

As illustrated in Figs. 17 to 20 each fuse cartridge MFC used in Figs. 21 and 22 has four fuse wires therein although any convenient number of wires may be used in 85 each cartridge. When four wire cartridges are used, upon each actuation of the handle 150 back and forth the left hand cap and its stem 156 rotates a quarter of a turn making a new fuse element connection. The spring 90 cam 162 is so arranged upon the wheel 161 that beginning with the return movement of the lever 150 upon each successive fourth actuation thereof (assuming that for the position of the cam shown in Fig. 22 the lever 95 has already been actuated twice) the spring cam rides over the head 169 and overcoming the spring 170 forces the opposite end 171 of the pin 168 against the other stem 157, the springiness of the cam spring 162 preventing buckling or sticking of the pin 168 while it is in engagement with the enlarged portion of the stem 157. When the fourth return movement is completed the cam spring 162 forces the rod 168 into engagement with 100 and connection to the reduced portion 172 of the stem 157. When the handle 150 is again actuated and released both stems 156—157 are actuated rotating both caps a quarter of a turn to new fuse wire positions, the 105 cam spring 162 remaining in engagement with the head 169 at least until the outward movement is completed when the cam spring 162 releases the head 169 allowing the rod spring 170 to move the rod out of engagement with the stem 157. When the handle 150 is released springs 173 pull the actuating member back, forcing both fuse caps 122 into a new fuse wire or element relation and holding them there. The number of actuations 110 necessary to form all the different combinations will vary with the number of fuse wires in each cartridge. The cam 162 will then be arranged differently for a different number of wires to control one of the fuse devices at 115 the right time to make these difference combinations.

When there are four fuse wires in each cartridge as illustrated, upon sixteen actuations of the member or handle 150 each successive 120

fuse wire of one cartridge will have been connected in circuit with the fuse wires of the other cartridge successively. This is a distinct advantage because heretofore, when one fuse of several blows out, it has been difficult to tell which fuse has blown. It has required time to replace one fuse and then another. By the construction herein described and shown any fuse wire of one device may be connected 10 with any fuse wire of the other device, determined by the number of actuations, making different combinations of the wires of the devices. The improvement illustrated in Figs. 21 and 22 also has the advantage over 15 the constructions of the other figures herein described in which, to change a fuse, it is necessary to actuate one external means and then another until two good fuse positions are secured. By utilizing a single actuating 20 member with the interposed mechanism all that is necessary is to continue to actuate the member until two good fuse wires or elements are connected, as indicated by lighting of the lamps or movement of the machinery utilizing 25 the power.

If so desired the fuse changing device 149 may be locked until the switch is opened. For this purpose I have illustrated hooks 174 extending over the actuating member in such 30 position as to prevent it from being pulled back until the hooks 174 are raised. These hooks are secured to a switch (not illustrated) although such switches are shown in other figures of the drawings.

It will be apparent to anyone skilled in the art that the handle 150 and fuses MFC must be properly insulated from each other, as by making the stems 156—7 and rod 168 of good strong insulating material. An advantage 35 of this invention is that existing types of fuse boxes may be utilized with little change in their construction. The enclosed multiple cartridge fuses such as illustrated in Figs. 21 and 22 are positioned just like 40 single fuse cartridges are at present but in the proper types of clip or socket. The fuse actuating device is added to the box at a convenient and available portion thereof. The actuating member extends through the cover 45 and enables the changes of fuses without opening the box, the box being closed and inaccessible. The single lever or actuating member simplifies the fuse changing procedure as no choice between several handles or 50 experimenting is necessary. If the lever is actuated long enough results will be obtained. When the fuse wires of either cartridge are exhausted the box can be opened without first removing any of the outside parts of the fuse 55 changing device and the old fuse cartridge replaced by a new one which is then connected up to the actuating device. The fuses employed can be available in quantities, that is, 60 are standard and are fireproof, each wire

being fully protected and enclosed and insulated from the others.

The invention insures full protection to the power companies against unauthorized access to the box and is a convenience and protection to the consumer. The invention is simple, easy to install in existing constructions, capable of replacements by standardized fuses which may be easily inserted and connected and fully protects against fire and shocks.

In Figs. 23 to 26 is disclosed a multiple fuse arrangement of the non-cartridge type and of the pluglike type, distinguishing from the latter type however in that the device is devoid of the threaded socket known as the "Edison base". The form illustrated comprises a plurality of plug like multiple fuse members which may be actuated by a single instrumentality from a point outside of the casing.

The base 175 comprises a pair of fuse member receiving sockets 176 adapted to receive the fuse members 177 and enclose them, fitting them closely. The base and sockets are formed or molded from porcelain or an insulating composition as a unitary single piece devoid of threads, receiving two multiple fuse members 177, and in this respect is unlike the usual socket members or base. Each socket 176 is provided with a central metal contact or terminal 178 located in the bottom of the socket and connected to the lead 179 formed or embedded in base 175. The contact 178 is preferably split to tightly engage the fuse device 177 and if so desired may be 90 spring pressed that is, mounted to be yielding axially to form a firm contact with member 177 when the latter is placed in position.

Likewise mounted in each socket 176 is a second contact or terminal 180 which is secured in the socket 176 at the upper end in spaced relation to contact 178 and which is in circuit with the lead 181 embedded in the base 175. The contact 180 has a free yielding spring end which is adapted to engage the fuse device 177 while allowing its rotation in either direction, the outer end 180^a being V shaped for this purpose.

The multiple fuse member 177 consists of a single molded or formed piece 182 which may be composed of porcelain or other suitable insulating material. The piece 182 is frusto conical in shape, being adapted to closely fit in the socket 176. Spaced around the periphery of the piece 182 are longitudinal ridges 183 forming grooves between them, the fusible elements 184 being located in the grooves and being electrically connected together and pressed into a recess 185 in the bottom of the piece 182 into which the contact 178 fits when 115 the fuse member 177 is placed in its socket. The upper ends 186 of the ridges 183 are wedge shape to allow the V shaped end 180^a

of contact 180 to slide over them in either direction when the fuse member is rotated, contact 180^a engaging the upper portions of the fuse elements 184 to complete the circuit through them. Each piece 182 has an actuating lug 187 formed on its upper end.

Thus when the member 177 is inserted into its socket 176 the contact 178 engages the common end of the several fuse elements in the axial recess 185 and the contact 180^a rides over the opposite ends of the fuse elements. By rotating the member 177 in either direction the fuse elements may be placed in circuit successively. In order to retain the fuse member 177 in position in its socket 176 and to form a complete enclosure for the fuse elements an annular metal cap 188 (Fig. 24) is threaded at 189 to each socket 176, the cap 188 having an overlapping portion 190 engaging the upper side of piece 182. If preferred instead of having a separate cap 188 for each fuse member a single cover 191 of insulating material (Fig. 23) may be utilized to enclose the two fuse members 177 and retain them in position. This cover 191 as shown in section (Fig. 23) closely fits over the base 175—176, retaining members 177 in their sockets and completely inclosing them in insulating material. The cover 191 can be secured in position by a screw 192 passing through the cover into the base 175.

The main feature of this invention is the simplification of the device and the reduced cost of installation and manufacture. Each device or fuse comprises two separable parts, the base (devoid of threads) and a unitary multiple fuse member which can be easily inserted and removed into and from the socket in the base, the fuse member being suitably retained therein. The expensive metal Edison threaded base is entirely eliminated in the construction, the device comprising a unitary base with one or two sockets and the multiple fuse member or members (likewise of unitary simple construction) insertable therein, the fusible elements however being completely enclosed by insulating material. The base 175 is permanent. Should a fuse blow out the member 177 is rotated to a new fuse element connection and when the fuse elements of any member are exhausted the member 177 can be easily removed and replaced, a supply of the latter being available.

As illustrated in Fig. 23 the lugs 187 project through the cover 191 whereby either fuse device may be actuated without removing the cover, that is, rotated to a new fuse element position. It is preferable however to enclose the base 175 and fuse members 177 in a metal casing 193 having a cover 194. The lugs 187 may be extended so that each device 177 may be actuated externally (in the manner shown in Fig. 1). I have illustrated however mechanism for actuating either or both fuse devices 177 by means of a single

instrumentality located outside of the cover whereby either fuse device may be actuated without opening the box or casing (and without unlocking it should it be locked). The means employed and the results obtained are similar to those illustrated in Figs. 21 and 22 and above described. The actuating means comprises a supporting plate 195 mounted upon the bottom of the cover 194 by means of a screw and washer 196 and in spaced relation to the cover. An actuating knob or thumb piece 197 is rotatably mounted in one end of the plate 195 and projects through an opening 198 in the cover 194. Secured to the knob 197 at a point below the plate 195 is a finger like member 199 having downwardly projecting spaced prongs 200 adapted to detachably engage opposite flat sides of a lug 187 whereby the lug and its fuse member 177 may be rotated. A star wheel 201 is rotatably mounted in the other end of plate 195 on an axis 202, the wheel 201 being located below the plate 195 and having prongs 203 detachable engaging opposite flat sides of the lug 187 of the other fuse member 177. The wheel 201 has a number of teeth 204 corresponding in number to the number of fuse elements on the member 187 (in the embodiment illustrated six). The operation of the device illustrated in Figs. 23 and 25 is as follows: Should a fuse blow out, the knob 197 is rotated (clockwise) until a good fuse is placed in circuit. Upon each complete rotation of the knob 197 the finger 199 engages a tooth 204 rotating the other fuse device counter clockwise a sixth of a turn placing it in a new fuse relation, the finger 199 having a sufficiently long radius as to describe an arc when rotated enabling it to disengage the star wheel 201 after each actuation of the latter. This arrangement while imparting a continuous step by step rotation to one fuse device, intermittently actuates the other a step so that the fuse elements can be connected in circuit in different combinations one with the other. The knob 197 should be continuously rotated until the lights again go on, since upon thirty six actuations or sixth turns of knob 197 all the fuse elements of one member 177 will have been connected in circuit with each fuse element of the other member 177. When it is desired to replace a fuse member 177 the cover 194 is removed which carries with it the actuating mechanism, the latter disengaging the lugs 187. The cover 191 or retainer 188 is then removed and the fuse member replaced and secured. The cover 194 is then replaced with the prongs 200—203 properly engaging the lugs 187. The finger 199 (Fig. 25) can also be rotated counter clockwise with similar results, as shown the first sixth of a turn in this case rotating both fuse members 177. The sockets 176 being rigidly and permanently secured to the base 175, the fuse mem-

bers 177 can be rotated in either direction without danger of unscrewing any of the parts, the parts 180^a, and 186 cooperating to allow movement in either direction. Thus in the use of the single actuating device the two members can be rotated in opposite directions, but being identical in construction, the members are standard for either fuse socket.

In Fig. 27 is illustrated an alternative or modified means 205 for retaining the fuse members 177 in position within their sockets 176. This means can be employed instead of the cover or retaining device 191 illustrated in Fig. 23.

The means 205 comprises a pair of connected or integral flanged annular members 206 adapted to fit around the tops of the sockets 176 and over the members 177 retaining them in place. The members or rings 206 have central openings 207 through which the lugs 187 project to allow their rotation.

The spectacles like retaining means 205 is so mounted that it can be raised and then rotated to a position at right angles to that position illustrated so that the fuse members 177 can be removed and replaced when exhausted.

The means employed for performing this function, and also for performing the additional function of retaining the members 177 in position under spring pressure, comprises a rod 208 secured centrally to the member 205 and slideable longitudinally in the base 175 between the sockets 176 as well as rotatably therein. The lower end of the rod 208 has a head 209 between which and a portion of the base is interposed a spring 210 coiled around the rod 208 and tending to draw the member 205 down firmly upon the sockets 176 and fuse members 177. The opposite end of the rod 208 has a ring 211 whereby the retaining means may be lifted and rotated out of the way to allow the insertion of new fuse members. After such new fuse members are inserted into place the member 205 is released and let down into retaining position. The spring construction herein described is such as to maintain the members 177 under spring pressure to compensate for irregularities of construction and to prevent binding of the members 177 when rotated to new fuse element positions, insuring ease of operation. The spring 210 also insures that the central fuse contact 185 will be maintained in close contact with the contact 178 at all times, compensating for wear due to the rotation of the members 177. The members 206 are so constructed as to completely enclose the fuse elements and may be composed of any suitable material such as metal or insulation. While in Fig. 27 is illustrated one means for retaining the members 177 in place under spring pressure, I have previously described how such spring pressure may be maintained by

spring mounting each contact 178 (Fig. 24). 65 Such spring pressure can be maintained by the cooperation of any of the securing or retaining means disclosed or their equivalents as defined in the claims.

I claim:—

1. A plurality of multiple fuse devices, and an actuating member for said devices including means for intermittently actuating one of said devices. 70

2. A plurality of multiple fuse devices each comprising fusible elements connectible in circuit, successively, a member for actuating said devices, and mechanism interposed between said member and said devices for connecting said elements in circuit in different combinations thereof upon actuation of the member. 75

3. A fuse box having a plurality of multiple fuse devices therein having fuse elements, and a single actuating member operable from the outside of said box for changing said elements within the box and including means for intermittently operating one of said devices to place said elements in circuit in different combinations. 80

4. A fuse box having therein sets of fuse receiving terminals, multiple fuse devices removably secured in said terminals and movable to change fuse elements, a single actuating member operable from the exterior of said box and comprising means for differentially operating said fuse devices for securing different combinations of the fuse elements in the circuit, said actuating means being disconnectible from the fuse devices to allow their removal from the box when exhausted. 90

5. A plurality of multiple fuse devices, each comprising a plurality of fusible elements, and a single actuating means for shifting said devices for connecting the elements in circuit, said means being arranged and constructed to successively connect in circuit each element of one device with the elements of the other device successively upon successive actuation of said means. 105

6. A plurality of multiple fuse devices, each having several fuse elements, a single actuating member for actuating one of the devices upon each actuation of the member, and means operated by said member for actuating the other device intermittently. 115

7. A multiple fuse device comprising a plurality of sockets having terminals, members carrying fuse elements rotatably mounted in said sockets and adapted to connect said elements successively to said terminals, a star wheel rotatable with one of said members, and means for actuating the other member and comprising a finger for intermittently rotating said star wheel and first member. 120

8. A multiple fuse device comprising a plurality of sockets having terminals, fuse ele-

ment carrying members rotatably mounted in said sockets to successively connect the elements to said terminals, a box enclosing said fuses, a cover for said box, and actuating means for said members, mounted on the inner side of said cover, accessible at the opposite side of the cover and movable to disengage the members when the cover is opened.

9. A multiple fuse comprising a plurality of sockets, fuse carrying members therein, a device retaining said members in place and including a spring for holding said members under spring pressure, said device being liftable against said spring and rotatable to allow inserting of new members.

FRED W. BAUM.
